ROOF CONSTRUCTION

Thomas I. High, Miami, Fla.

Application January 2, 1940, Serial No. 312,134

2 Claims. (CL. 103—1)

The present invention relates to new and useful improvements in steel roof or span constructions and has for its primary object to provide, in a manner as hereinafter set forth, a structure of this character of novel form whereby a comparatively large area may be covered without the necessity of using intermediate supports, such as posts, pillars, etc.

Another very important object of the invention is to provide a roof or span construction of the aforementioned character which may be expeditiously erected and taken down without the necessity of using special tools or machinery.

Still another important object of the invention is to provide a roof or span structure of the character described which may be of any desired dimensions.

Other objects of the invention are to provide a roof or span construction which will be comparatively simple, strong, durable, light in weight and which may be manufactured and erected at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of an embodiment of the invention.

Figure 2 is an elevational view of an end portion of the roof.

Figure 3 is a view in vertical section through an intermediate portion of the roof.

Figure 4 is a detail view in perspective of one of the plates.

Figure 5 is a cross sectional view through a portion of the roof.

Figure 6 is a detail view in perspective of one of the arch brackets.

Figure 7 is a detail view in perspective of one of the arch segments.

Figure 8 is a detail view in perspective of one of the arch braces.

Figure 9 is a detail view in elevation of one of the rings for the crossed arch braces.

Figure 10 is a view in side elevation of a portion of another form of the invention.

Referring now to the drawings in detail, it will be seen that the reference numeral 1 designates a pair of spaced walls. Mounted on the walls 1 are metallic plates 2 which are secured by anchors 3. Extending between the plates 2 on the walls 1

is a tie rod 4 to prevent spreading, this tie rod including turnbuckles 5 for tightening.

Rigidly secured at spaced points on the plates 2 are brackets 6. The reference numeral 7 designates generally a plurality of spaced arches of suitable metal which are mounted on the brackets 6. Each arch 7 comprises a plurality of segments 8 having overlapping end portions rigidly secured together through the medium of bolts 9.

Extending between the arches 7 are pairs of crossed braces 10. The braces 10 are provided with eyes 11 on their ends which accommodate the bolts 9. Thus, the same bolts which secure the segments 8 together also secure the braces 10 to the arches. Rings 11 connect the crossed braces 10 at the points where they intersect.

Referring now to Figure 1 of the drawings, it will be observed that struts 12 are provided for strengthening the arches 7 against distortion or collapsing. The ends of the struts 12 are secured to the joints of the arch segments 8. It will also be noted that the struts 12 are of sufficient length to skip several of the segments 8 of the arches 7.

The reference numeral 13 designates roofing mounted on the arches 7. Of course, the roofing 13 conforms to the curvature of the arches 7 and, referring to Figure 5 of the drawings, it will be seen that the sections of said roofing are of sufficient width to extend between the adjacent arches. The roofing sections 13 comprise overlapping marginal portions 21 which rest on the arches 7. The portions 21 are provided with interlocked V portions 14 which extend adjacent the opposite sides of the arches 7. Then, the roofing is firmly secured to the arches through the medium of J bolts 15. Washers 16 of suitable material are provided beneath the bolt nuts 17 for preventing leakage around the bolts.

It will thus be seen that a metallic roof or span has been provided of such construction as to obviate intermediate supporting pillars, etc. It will also be observed that the structure may be expeditiously erected without the use of special equipment. Further, the structure may be taken down if desired and there will be practically no loss of material.

In Figure 10 of the drawings there is illustrated a modification to be used when unusual strength is desired. This modification comprises inner and outer arches 18 and 19, respectively, which are spaced from each other through the medium of braces 20. In other respects, this modification is substantially similar in construc-

tion to that form of the invention shown in Figs. 1 to 9, inclusive.

It is believed that the many advantages of a steel roof or span construction in accordance with the present invention will be readily understood and although preferred embodiments are as illustrated and described, it is to be understood that further modifications and changes in the details of construction may be resorted to which will fall within the scope of the invention as claimed.

What is claimed is:

1. A structure of the class described comprising a plurality of spaced arches, each arch including a plurality of metallic segments having overlapping end portions, pairs of crossed braces extending between the arches and terminating,

5 at their ends, in eyes engaged with the joints of the arch segments, securing elements passing through the eyes and the overlapping end portions of the segments for rigidly securing said segments and crossed braces together, and rings connecting the crossed braces at the points where they intersect.

10 2. A structure of the class described comprising a plurality of spaced arches, roofing mounted on said arches, said roofing comprising sections including overlapping marginal portions resting on the arches, said overlapping portions including substantially V-shaped interlocked portions on opposite sides of the arches, and means for anchoring the roofing sections on said arches.

15 THOMAS I. HIGH.
